RACE GAME APPARATUS

Patrick Gilbert Kennedy, London, England

Application March 16, 1933, Serial No. 661,061
In Great Britain May 12, 1932

19 Claims. (Cl. 273—86)

This invention relates to race game apparatus and it has for its object to provide novel and unique means designed to enhance the interest of the competitors or players.

5 The spirit of competition is characteristic of the present invention which is directed to place within the reach of many, the experiences of those who are able to take part as actual competitors in automobile racing on the full scale and with this and other objects in view my invention consists in the novel combinations and arrangements of parts described in the following specification, illustrated in the annexed drawings and more particularly pointed out in appended claims.

10 I have observed that one of the principal attractions in full size motorcar racing is the lateral skidding or slewing of the vehicle during the negotiation of curves or corners, and that 20 on the degree of skill displayed in taking such curves or corners depends in many cases the final placing of the competitors.

One of the objects of the invention is the provision of race game apparatus in which firstly, 25 a plurality of tracks are provided with curves or corners, and secondly, a plurality of miniature electrically-driven vehicles are guided by said tracks by guiding means positioned at the front of each vehicle to hold the front of the vehicle 30 to the track and allow the rear to slew and come in contact with the guide when taking the curves or corners if taken at too high a speed. So far as I am aware, such slewing motion on curves in simulation of motor car skidding is a novel feature in race game apparatus.

Another object is the provision of a simple competitor-operated control by which the supply of current to the vehicle may be interrupted allowing the competitor to concentrate his attention 40 solely on the speed of the vehicle and particularly the speed at which the curves are negotiated.

Another object is the provision of race game apparatus by which each competitor has an equal 45 opportunity to traverse the course in the same time for the display of equal skill, so that the skill of the operator is the only factor affecting the result of the race. The game has therefore greater attraction than where devices outside 50 the control of the operator are employed to produce variations in speed. Equity of opportunity between the competitors is affected by two factors; firstly by the effective speed of the vehicles; and secondly by the character of the path traversed by the vehicles. The combined effect of

these two influences should be such that given equal skill on the part of the competitors, the time taken by each vehicle to cover its relevant course should be substantially the same.

The several tracks are preferably of equal length and the speeds of the vehicles are initially designed to be the same but since exact equality of speed is difficult of attainment under practical manufacturing limitations and variations, it is desirable to provide for adjustment of the power supplied to the different vehicles conveniently by means of a variable resistance combined with the electric circuit wherein is included each vehicle. A state of balance, in terms of time can thereby be obtained between the several tracks and their relevant vehicles. Other balancing means may be used such as an increased ohmic resistance of certain sections of the conductor rails from which the vehicles derive their electric power, or by the provision of dead sections of the conductor rail where the supply of electric current is discontinued.

Another feature of my invention is the provision of a compact formation of the tracks by means of closed circuits with sections at different levels connected by gradients. The tracks are arranged side by side so that the competitors and spectators have a clear view as the machines traverse the tracks, the number of tracks and vehicles being as desired.

30 In the drawings:—

Figure 1 is a plan view of one form of track in accordance with my invention.

Figure 2 is an isometric view of a track of similar formation to that shown in Figure 1.

Figure 3 illustrates in plan another form of equi-length tracks.

Figure 4 is a cross-sectional elevation of a guide rail which serves also as a conductor rail.

Figures 5 and 6 are cross-sectional elevations 40 of alternative constructions of combined rails.

Figure 7 is an elevation of a miniature automobile.

Figure 8 is a plan view of the automobile shown in Figure 7 and Figure 9 is an end elevation 45 thereof.

Figure 10 is an electric wiring diagram.

In Figure 1 is shown a lay-out for a six-track apparatus comprising tracks 1, surrounded by a barrier 2 to leave an inter-space 3 for the spectators; electric control buttons 4 mounted on top of the barrier 2, one for each competitor; an outer barrier 5 disposed to leave a space 6 for the competitors; an entrance 7 and exit 8 for players; and a pay desk 9 at the entrance 7.

55

So that all competitors shall have an equal chance, providing that equal skill is displayed, the paths to be traversed are designed, in one aspect of the game, to be of equal length or 5 perimeter and this object is capable of attainment by various formations of tracks. The shape or configuration shown in Figure 1 is a convenient one and includes a long straight section 11 which serves as the starting and finishing parts of the 10 tracks. The starting section 11 may be followed by a semi-circular curve 12 which joins a straight section 13 arranged to pass below another portion 14 of the track situated at a higher level. In this example, the tracks are arranged at two 15 different levels connected by one incline and one decline with three bridges or crossings, but there may be several general levels, with additional gradients other than those which connect the general levels. The semi-circular curves 12, 18 20 at the ends of the starting and finishing straight section 11 are of mean equal radius, and similarly the curves 16, 17 at the ends of the upper section (which includes an angle a little in excess of 180°) are of equal mean radius. The remaining curves 18, 19 are likewise balanced for mean 25 radius, and as the straight sections are respectively of common length, it will be apparent that the aggregate distance for each track is identical. The crossings are indicated at 14, 20 and 21, the 30 incline at 22 and the decline at 23. The construction of the tracks may include plywood platforms 24 built upon timber supports 25 as indicated in Figure 2, or moulded composition may be utilized as the basic material.

35 In Figure 3 I have illustrated in diagrammatic form another configuration of equi-length tracks comprising four curves 26 connected by four straight sections 27, resulting in a petal form. There are three general levels 28, 29 and 30 the 40 last-mentioned being the lowest. These general level differences may occur only at the crossings, or may be extended to the petal sections. The crossings involve two descents and two inclines.

45 The driving force is electrical and provision is made to supply current to the vehicles by way of feeder or conductor rails embodied in the guiding rail provided one for each machine on or in the track surface. In Figure 4, two metal conductors 31 are embedded in a hard rubber rail 22 extruded for convenience, said conductors being of T shaped cross-section. In Figure 5 the conductor rails 31 are attached to and separated from each other by a strip of hard rubber, fibre 50 or other insulating material 33. This construction allows connection of adjacent lengths by means of a sleeve 34 of metal which can be soldered to ensure good electrical conductivity. A further construction shown in Figure 6 includes 55 conductor rails of channel cross-section separated by an insulating strip and conveniently fixed down to the track platform by nails 35.

60 While I have illustrated in Figures 7, 8 and 9 a miniature automobile, other vehicles may be used, the general shape of the body or cover being suitably adapted to emulate that of, for example, an airplane, airship, motor boat, etc. while retaining the characteristics of the invention by the provision of a machine which is subject to 65 the natural law of centrifugal force for the production of skidding and consequential loss of speed on curves or corners unless the speed at which they are negotiated is reduced by the player below the speed of travel on the straight. The 70 miniature automobile shown in Figures 7, 8 and 9

comprises a body 36 with rear axle 37 and driving wheels 38 coupled through gearing 39 with an electric motor 40. At the front, the car is supported upon a front axle 41 and steering wheels 42, said axle being in the form of a beam 5 pivoted loosely at 43 to the body of the car to allow the rear end to move under the influence of centrifugal force when rounding curves or corners for the purpose of diminishing speed if the curve or corner is taken at a speed exceeding a pre-determined optimum velocity. The vehicle is guided at the front by contact with the upstanding guide rail, and hinged contact 10 slippers 44 may be adapted both to supply current to the machine and to cause the vehicle to follow 15 the guide rail.

In the diagram of electric connections shown in Figure 10, 45 is a source of electric power either battery or mains; 46 and 47 are conductor rails; 48 are the variable resistances in circuit with the 20 respective conductor rails and relevant vehicles; and 4 are the switches, one for each vehicle and associated circuit, by which the competitors are able to control the speed of their respective vehicles, by interrupting the relevant circuit and 25 thereby cutting off the supply of current thereto. For convenience in bringing the machines to a standstill at the end of a race, a dead section of track may be incorporated and combined with means adapted to bring said dead section into 30 operation at the correct time before the end of the last lap when a plurality of laps constitutes a race. Such timing may be performed manually or automatically. In the former case, a switch 49 is wired to enable a section 50 of each pair 35 of conductor rails to be cut out by the attendant after the last vehicle has commenced the ultimate lap.

40 While it is preferable to employ equi-length tracks and similar machines with a view to obtaining equity of opportunity for the display of equal skill on the part of competitors, it is found that the limitations of commercial manufacture make it difficult to realize identity of speed as between one machine and another and therefore 45 it is desirable to provide some means for balancing the combined effect of track and initial machine speed. To this end, the elapsed time per circuit or lap can be adjusted and brought into identity by adjustment of the variable resistances 48. As a corollary it follows that the 50 invention includes a plurality of tracks which are of unequal length and/or with different curvatures, compensation for which is obtained by adjusting the maximum speed of the various vehicles by means of the resistances 48. Unlike 55 gradients may be dealt with in a similar manner. Alternatively, the ohmic resistance of some of the sections of conductor rail may be different as between one circuit and another circuit to 60 produce an equal time-basis for each competitor.

The players having taken up their positions in front of the control switches and the vehicles brought to the starting line, the game is started by closing the master switch 51. Figure 10, or the 65 switch 49 may be arranged to perform also this function. The machines thus set in motion proceed along the straight section 11 to enter the first curve. It will be observed that the innermost machines have to traverse the shortest path 70 on the first bend and on the last bend whereas on the two intermediate main curves, they are on the outermost track. Conversely, the outermost machine traverses the longest path on the first and last bends, and the shortest path on the 75

two intermediate bends. The maximum speed when the electric power is not diminished by a competitor, is sufficiently high to produce lateral skidding or side-slipping on some or all of the 5 curves or corners by the effect of centrifugal force, and therefore the speed of negotiation must be reduced by the player by cutting off the supply of current. Conveniently the control is in the form of a push-button mounted to move up and 10 down in a surround which forms a rest for the player's hand. The element of skill resides in the player's control of the speed at which the curves are taken, and the player who displays the most skill in taking the curves at optimum 15 speed without skidding sufficiently to slow the vehicle, wins the race. The machines are constructed to run at high speeds so that it is necessary to cut out before reaching the curves or some of them, thereby to enhance the pleasure and 20 entertainment of the players and onlookers.

The apparatus described herein permits of a reproduction on an inexpensive scale of the thrills and excitement hitherto associated with motor car racing on the full size scale. When the rear 25 of the machine slews under the influence of centrifugal force, one of the rear wheels comes into contact with the upstanding guide rail and is thereby slowed down, or the dimensions of the machine may be such that the body is brought 30 into contact with one of the front wheels, or otherwise slowed down. It may be that one of the rear wheels jumps the guide rail but as the motor continues to drive, the effect is generally 35 that the rear wheels will creep over the guide rail until in the correct position for normal running and driving. Very excessive speeds on the curves 52 Figure 9 on the contact slipper 44 will hold the 40 vehicle to the guide rail in a vertical direction upwards of the track.

A signal, lamp, or other indicator may be combined with each track so that the competitors 45 may have a visual indication as to which is the first car to pass the winning post. Such device is desirable to avoid disputes between players, in view of the high speeds attained and the close 50 finishes which may occur.

To check the number of races run, even when 55 the complement is not a full one, a counting means may be used and operated by each car on each lap so that the takings may be verified. Coin-free apparatus may be employed in combination with the apparatus described whereby 60 the players may themselves start the game, the coin either operating through mechanical means or being utilized as an element of the electric circuits of the vehicles.

Apparatus as described herein incorporates two 65 desirable features; provision for the exercise of skill; and an embodiment of the spirit of competition; allied to an equity of opportunity for the exercise of equal skill, which render the game one of particular pleasure and interest.

Having thus described my invention; what I 70 claim is:—

1. Race game apparatus for a plurality of competitors comprising in combination a plurality of tracks forming closed circuits, curves or corners thereon; a plurality of miniature electrical 75 driven automobiles or like vehicles adapted to traverse said tracks and to be guided thereby, each of said vehicles including a front axle, guiding means on said axle to engage the relevant track, and an articulated connection between

said axle and the main structure of the vehicle to allow the rear of the vehicle to slew on one or more of said curves or corners and the rear wheels to come into contact with the track, said vehicles being constructed to traverse said tracks at a 5 speed which will cause the vehicles to slew at the rear on one or more of the curves or corners unless the speed of negotiation thereof is reduced by the competitor; a competitor-operated speed control means for each competitor operable at 10 will to control vehicle speed on one or more of said curves or corners; and a plurality of electric circuits including said vehicles and said control means the character of said tracks and the speed of the respective vehicles being so combined 15 that the time per lap for traversing each of the several tracks is substantially equal for equal skill in controlling the speed of the vehicles for optimum speed on the said curves or corners.

2. Race game apparatus for a plurality of competitors comprising in combination a plurality of tracks forming closed circuits, curves or corners thereon; a plurality of miniature electrically-driven automobiles or like vehicles adapted to traverse said tracks and to be guided thereby, 25 each of said vehicles including a front axle, guiding means on said axle to engage the relevant track, and an articulated connection between said axle and the main structure of the vehicle to allow the rear of the vehicle to slew on one or more 30 of said curves or corners and the rear wheels to come into contact with the track, said vehicles being constructed to traverse said tracks at a speed which will cause the vehicles to slew at the rear on one or more of the curves or corners unless 35 the speed of negotiation thereof is reduced by the competitor; a competitor-operated speed control means for each competitor operable at will to control vehicle speed on one or more of said curves or corners; a plurality of electric circuits 40 including said vehicles and said control means; and means for adjusting the electrical resistance of said electric circuits for equalizing the time taken per lap by the several vehicles to traverse their relevant tracks the character of said tracks 45 and the speed of the respective vehicles being so combined that the time per lap for traversing each of the several tracks is substantially equal for equal skill in controlling the speed of the vehicles for optimum speed on the said curves or 50 corners.

3. Race game apparatus for a plurality of competitors comprising in combination a plurality of tracks forming closed circuits, curves or corners thereon; a plurality of miniature electrical 55 driven automobiles or like vehicles adapted to traverse said tracks and to be guided thereby, each of said vehicles including a front axle, guiding means on said axle to engage the relevant track, and an articulated connection between 60 said axle and the main structure of the vehicle to allow the rear of the vehicle to slew on one or more of said curves or corners and the rear wheels to come into contact with the track, said vehicles being constructed to traverse said tracks at a speed which will cause the vehicles to slew 65 at the rear on one or more of the curves or corners unless the speed of negotiation thereof is reduced by the competitor; a competitor-operated speed control means consisting of an on-and-off 70 electric switch for each competitor operable at will for controlling vehicle speed on one or more of said curves or corners; and a plurality of electric circuits including said vehicles and said switches the character of said tracks and the 75

speed of the respective vehicles being so combined that the time per lap for traversing each of the several tracks is substantially equal for equal skill in controlling the speed of the vehicles for optimum speed on the said curves or corners.

4. Race game apparatus for a plurality of competitors comprising in combination a plurality of tracks forming closed circuits, curves or corners thereon; a plurality of miniature electrically-driven automobiles or like vehicles adapted to traverse said tracks and to be guided thereby, each of said vehicles including a front axle, guiding means on said axle to engage the relevant track, and an articulated connection between said axle and the main structure of the vehicle to allow the rear of the vehicle to slew on one or more of said curves or corners and the rear wheels to come into contact with the track, said vehicles being constructed to traverse said tracks at a speed which will cause the vehicles to slew at the rear on one or more of the curves or corners unless the speed of negotiation thereof is reduced by the competitor; a competitor-operated speed control means for each competitor consisting of an on-and-off electric switch operable at will for controlling vehicle speed on one or more of said curves or corners; a plurality of electric circuits including said vehicles and said switches; and means for adjusting the electrical resistance of said electric circuits for equalizing the time taken per lap by the several vehicles to traverse their relevant tracks the character of said tracks and the speed of the respective vehicles being so combined that the time per lap for traversing each of the several tracks is substantially equal for equal skill in controlling the speed of the vehicles for optimum speed on the said curves or corners.

5. Race game apparatus for a plurality of competitors comprising in combination a plurality of tracks forming closed circuits, curves or corners thereon; a plurality of miniature electrically-driven automobiles or like vehicles adapted to traverse said tracks and to be guided thereby, each of said vehicles including a front axle, current pick-up and guiding devices on said axle to engage the relevant track, and an articulated connection between said axle and the main structure of the vehicle to allow the rear of the vehicle to slew on one or more of said curves or corners and the rear wheels to come into contact with the track, said vehicles being constructed to traverse said tracks at a speed which will cause the vehicles to slew at the rear on one or more of the curves or corners unless the speed of negotiation thereof is reduced by the competitor; conductor rails for each track engaged by said current pick-up device to supply current to the relevant vehicle; a competitor-operated speed control means for each competitor operable at will for controlling vehicle speed on one or more of said curves or corners; and a plurality of electric circuits including said conductor rails, current pick-ups, vehicles, and speed control means the character of said tracks and the speed of the respective vehicles being so combined that the time per lap for traversing each of the several tracks is substantially equal for equal skill in controlling the speed of the vehicles for optimum speed on the said curves or corners.

6. Race game apparatus for a plurality of competitors comprising in combination a plurality of tracks forming closed circuits, curves or corners thereon, electric conductor rails for each track; a plurality of miniature electrically-driven auto-

mobiles or like vehicles adapted to traverse said tracks and to be guided thereby, each of said vehicles including a front axle, current pick-up and guiding devices on said axle to contact with said conductor rails and supply current to said vehicle, and an articulated connection between said axle and the main structure of the vehicle to allow the rear of the vehicle to slew on one or more of said curves or corners and the rear wheels to come into contact with the track, said vehicles being constructed to traverse said tracks at a speed which will cause the vehicles to slew at the rear on one or more of the curves or corners unless the speed of negotiation thereof is reduced by the competitor; a competitor-operated speed control means for each competitor operable at will for controlling vehicle speed on one or more of said curves or corners; a plurality of electric circuits including said conductor rails current pick-ups vehicles and speed control means; and means for adjusting the electrical resistance of said electric circuits for equalizing the time taken per lap by the several vehicles to traverse their relevant tracks the character of said tracks and the speed of the respective vehicles being so combined that the time per lap for traversing each of the several tracks is substantially equal for equal skill in controlling the speed of the vehicles for optimum speed on the said curves or corners.

7. Race game apparatus for a plurality of competitors comprising in combination a plurality of tracks forming closed circuits, curves or corners thereon, electric conductor rails for each track; a plurality of miniature electrically-driven automobiles or like vehicles adapted to traverse said tracks and to be guided thereby, each of said vehicles including a front axle, current pick-up and guiding devices on said axle to contact with said conductor rails and supply current to said vehicle, and an articulated connection between said axle and the main structure of the vehicle to allow the rear of the vehicle to slew on one or more of said curves or corners and the rear wheels to come into contact with the track, said vehicles being constructed to traverse said tracks at a speed which will cause the vehicles to slew at the rear on one or more of the curves or corners unless the speed of negotiation thereof is reduced by the competitor; a competitor-operated on-and-off electric switch for each competitor operable at will for controlling vehicle speed on one or more of said curves or corners; a plurality of electric circuits including said conductor rails current pick-ups vehicles and on-and-off switches; and means for adjusting the electrical resistance of said electric circuits for equalizing the time taken per lap by the several vehicles to traverse their relevant tracks the character of said tracks and the speed of the respective vehicles being so combined that the time per lap for traversing each of the several tracks is substantially equal for equal skill in controlling the speed of the vehicles for optimum speed on the said curves or corners. 30 35 40 45 50 55 60

8. Race game apparatus for a plurality of competitors comprising in combination a plurality of tracks forming closed circuits, curves or corners thereon, electric conductor rails for each track; a plurality of miniature electrically-driven automobiles or like vehicles adapted to traverse said tracks and to be guided thereby, each of said vehicles including a front axle, current pick-up and guiding devices on said axle to contact with said conductor rails and supply current to said vehicle, and an articulated connection between said front axle and the main structure of the ve- 75

- hicle to allow the rear of the vehicle to slew on one or more of said curves or corners and the rear wheels to come into contact with the track, said vehicles being constructed to traverse said 5 tracks at a speed which will cause the vehicles to slew at the rear on one or more of the curves or corners unless the speed of negotiation thereof is reduced by the competitor; a competitor-operated on-and-off electric switch for each competitor operable at will for controlling vehicle speed on one or more of said curves or corners; and a plurality of electric circuits including said conductor rails, hinged contact slippers vehicles and speed control means; and means for adjusting the electrical resistance of said electric circuits for initially equalizing the time taken per lap by the several vehicles to traverse their relevant tracks 10 the character of said tracks and the speed of the respective vehicles being so combined that the time per lap for traversing each of the several tracks is substantially equal for equal skill in controlling the speed of the vehicles for optimum 15 speed on the said curves or corners.
11. Race game apparatus for a plurality of competitors comprising in combination a plurality of tracks, curves or corners thereon, a pair of electric conductor rails for each of said tracks; 20 a plurality of miniature electrically-driven automobiles or like vehicles adapted to traverse said tracks and to be guided thereby, each of said closed circuits, curves or corners thereon, electric conductor rails for each track; a plurality of 25 miniature electrically-driven automobiles or like vehicles adapted to traverse said tracks and to be guided thereby, each of said closed circuits, curves or corners thereon, electric conductor rails for each track; a plurality of 30 miniature electrically-driven automobiles or like vehicles adapted to traverse said tracks and to be guided thereby, each of said vehicles including a front axle, contact slippers hinged on said axle to contact with said conductor 35 rails for supplying current to, and guiding the front of said vehicle, and an articulated connection between said front axle and the main structure of the vehicle to allow the rear of the vehicle to slew on one or more of said curves or corners and the rear wheels to come into contact with the track, said vehicles being constructed to traverse said tracks at a speed which will cause the vehicles to slew at the rear on one or more of the curves or corners unless the speed of negotiation thereof is reduced by the competitor; a competitor-operated on-and-off electric switch for each competitor operable at will for controlling vehicle speed on one or more of said curves or corners; a plurality of electric circuits including 40 said conductor rails hinged contact slippers vehicles and on-and-off switches; and means for adjusting the electrical resistance of said electric circuits for initially equalizing the time taken per lap by the several vehicles to traverse their relevant tracks the character of said tracks and the speed of the respective vehicles being so combined that the time per lap for traversing each of the several tracks is substantially equal for equal skill in controlling the speed of the vehicles for optimum 45 speed on the said curves or corners.
12. Race game apparatus for a plurality of competitors comprising in combination a plurality of closed-circuit equi-length tracks, curves or corners thereon; a plurality of miniature electrically-driven automobiles or like vehicles adapted to traverse said tracks and to be guided thereby, each of said vehicles including a front axle, guiding means on said axle to engage the relevant track, and an articulated connection between said axle and the main structure of the vehicle to allow the rear of the vehicle to slew on one or more of said curves or corners and the rear wheels to come into contact with the track, said vehicles being constructed to traverse said 50 tracks at a speed which will cause the vehicles to slew at the rear on one or more of the curves or corners unless the speed of negotiation thereof is reduced by the competitor; a competitor-operated speed control means for each competitor operable at will to control vehicle speed on one or more of said curves or corners; and a plurality of electric circuits including said tracks said vehicle and said control means the character of said tracks and the speed of the respective vehicles 55
10. Race game apparatus for a plurality of competitors comprising in combination a plurality of tracks, curves or corners thereon, a pair of electric conductor rails for each of said tracks; a plurality of miniature electrically-driven automobiles or like vehicles adapted to traverse said tracks and to be guided thereby, each of said vehicles including a front axle, contact slippers hinged on said axle to contact with said conductor rails for supplying current to and guiding the front of said vehicle, and an articulated connection between the said front axle and the main structure of the vehicle to allow the rear of the vehicle to slew on one or more of said curves or corners and the rear wheels to come into contact with the track, said vehicles being constructed to traverse said tracks at a speed which will cause the vehicles to slew at the rear on one or more of the curves or corners unless the speed of negotiation thereof is reduced by the competitor; a competitor-operated speed control means for each competitor operable at will to control vehicle speed on one or more of said curves or corners; and a plurality of electric circuits including said tracks said vehicle and said control means the character of said tracks and the speed of the respective vehicles 60
15. and the speed of the respective vehicles being so combined that the time per lap for traversing each of the several tracks is substantially equal for equal skill in controlling the speed of the vehicles for optimum 65 speed on the said curves or corners.
20. Race game apparatus for a plurality of competitors comprising in combination a plurality of tracks, curves or corners thereon, a pair of electric conductor rails for each of said tracks; a plurality of miniature electrically-driven automobiles or like vehicles adapted to traverse said tracks and to be guided thereby, each of said vehicles including a front axle, contact slippers hinged on said axle to contact with said conductor rails for supplying current to and guiding the front of said vehicle, and an articulated connection between the said front axle and the main structure of the vehicle to allow the rear of the vehicle to slew on one or more of the curves or corners unless the speed of negotiation thereof is reduced by the competitor; a competitor-operated speed control means for each competitor operable at will to control vehicle speed on one or more of said curves or corners; and a plurality of electric circuits including said tracks said vehicle and said control means the character of said tracks and the speed of the respective vehicles 70
25. and the speed of the respective vehicles being so combined that the time per lap for traversing each of the several tracks is substantially equal for equal skill in controlling the speed of the vehicles for optimum 75 speed on the said curves or corners.

being so combined that the time per lap for traversing each of the several tracks is substantially equal for equal skill in controlling the speed of the vehicles for optimum speed on the said curves or corners.

13. Race game apparatus for a plurality of competitors comprising in combination a plurality of closed-circuit equi-length tracks, curves or corners thereon; a plurality of miniature electrically-driven automobiles or like vehicles adapted to traverse said tracks and to be guided thereby, each of said vehicles including a front axle, guiding means on said axle to engage the relevant track, and an articulated connection between said axle and the main structure of the vehicle to allow the rear of the vehicle to slew on one or more of said curves or corners and the rear wheels to come into contact with the track, said vehicles being constructed to traverse said tracks at a speed which will cause the vehicles to slew at the rear on one or more of the curves or corners unless the speed of negotiation thereof is reduced by the competitor; a competitor-operated speed control means for each competitor operable at will to control vehicle speed on one or more of said curves or corners; a plurality of electric circuits including said tracks, said vehicles and said speed control means; and means for initially adjusting the electrical resistance 30 of said electric circuits for equalizing the time taken per lap by the several vehicles to traverse their relative tracks, the character of said tracks and the speed of the respective vehicles being so combined that the time per lap for traversing each of the several tracks is substantially equal for equal skill in controlling the speed of the vehicles for optimum speed on the said curves or corners.

14. Race game apparatus for a plurality of competitors comprising in combination closed-circuit equi-length tracks, curves or corners thereon, electric conductor rails for each track; a plurality of miniature automobiles or like vehicles adapted to traverse said tracks and to be guided thereby, each of said vehicles including a rear axle, an electric driving motor operatively coupled thereto, a front axle, current pick-up and guiding devices on said axle to contact with said conductor rails and supply current to said motor, and an articulated connection between said front axle and the main part of the vehicle structure to allow the rear of the vehicle to slew on one or more of said curves or corners and the rear wheels to come into contact with the track, said vehicles being constructed to traverse said tracks at a speed which will cause the vehicles to slew at the rear on one or more of the curves or corners unless the speed of negotiation thereof is reduced by the competitor; a competitor-operated electric switch for each competitor operable at will for controlling vehicle speed on one or more of said curves or corners; and a plurality of electric circuits including said conductor rails, current pick-ups, electric motors and on-and-off switches, the character of said tracks and the speed of the respective vehicles being so combined that the time per lap for traversing each of the several tracks is substantially equal for equal skill in controlling the speed of the vehicles for optimum speed on the said curves or corners.

15. Race game apparatus for a plurality of competitors comprising in combination a plurality of two-level closed-circuit tracks each comprising a lower part having a starting and finishing straight run and a curve at each end of said

straight run, an upper part having a straight run parallel to said starting and finishing straight run and a curve at each end of said straight run, gradients connecting the said low level curves with the said high level curves; a plurality of miniature electrically-driven automobiles or like vehicles adapted to traverse said tracks and to be guided thereby, each of said vehicles including a front axle, guiding means on said axle to engage the relevant track, and an articulated connection between said front axle and the main structure of the vehicle to allow the rear of the vehicle to slew on one or more of said curves or corners and the rear wheels to come into contact with the track, said vehicles being constructed to traverse said tracks at a speed which will cause the vehicles to slew at the rear on one or more of the curves or corners unless the speed of negotiation thereof is reduced by the competitor; a competitor-operated speed control means for each competitor operable at will to control vehicle speed on one or more of said curves or corners; and a plurality of electric circuits including said tracks, vehicles and speed control means, the character of said tracks and the speed of the respective vehicles being so combined that the time per lap for traversing each of the several tracks is substantially equal for equal skill in controlling the speed of the vehicles for optimum speed on the said curves or corners.

16. Race game apparatus for a plurality of competitors comprising in combination a plurality of two-level closed-circuit equi-length tracks, each track comprising a lower part with a starting and finishing straight run and a curve at each end of said straight run, an upper part with a straight run and a curve at each end of said straight run, and gradients connecting said low level curves with said high level curves, conductor rails on said tracks; a plurality of miniature automobiles or like vehicles adapted to traverse said tracks and to be guided thereby, each of said vehicles including a rear axle, an electric motor operatively coupled to said axle, a front axle, contact slippers hinged to said front axle to engage said conductor rails for supplying current to said motor and guiding the front of the vehicle, and a hinged connection between said axle and the main part of the vehicle structure; a competitor-operated electric switch for each competitor operable at will to control vehicle speed on one or more of said curves or corners; and a plurality of electric circuits including said conductor rails, said contact slippers, said electric motors, and said electric switches, the character of said tracks and the speed of the respective vehicles being so combined that the time per lap for traversing each of the several tracks is substantially equal for equal skill in controlling the speed of the vehicles for optimum speed on the said curves or corners.

17. Race game apparatus for a plurality of competitors comprising in combination a plurality of two-level closed-circuit equi-length tracks, each track comprising a lower part with a starting and finishing straight run and a curve at each end of said straight run, an upper part with a straight run and a curve at each end of said straight run, and gradients connecting said low level curves with said high level curves, a pair of conductor rails on each of said tracks; a plurality of miniature automobiles or like vehicles adapted to traverse said tracks and to be guided thereby, each of said vehicles including a rear axle, an electric motor operatively coupled to said

rear axle, a front axle, contact slippers hinged to said front axle to engage said conductor rails for supplying current to said motor and guiding the front of the vehicle, and a hinged connection between said front axle and the main part of the vehicle structure to allow the rear of the vehicle to slew on one or more of said curves or corners and the rear wheels to come into contact with the track, said vehicles being constructed to traverse said tracks at a speed which will cause the vehicles to slew at the rear on one or more of the curves or corners unless the speed of negotiation thereof is reduced by the competitor; a competitor-operated speed control means for each competitor operable at will to control vehicle speed on one or more of said curves or corners; a plurality of electric circuits including said conductor rails, contact slippers, electric motors, and speed control means; and means for adjusting the electrical resistance of said electric circuits for initially equalizing the time taken per lap by the several vehicles to traverse their relevant tracks the character of said tracks and the speed of the respective vehicles being so combined that the time per lap for traversing each of the several tracks is substantially equal for equal skill in controlling the speed of the vehicles for optimum speed on the said curves or corners.

18. Race game apparatus for a plurality of competitors comprising in combination a plurality of tracks forming closed circuits, curves or corners thereon; a plurality of miniature electrically driven automobiles or like vehicles adapted to traverse said tracks and to be guided thereby, each of said vehicles including a front axle unit comprising an axle beam supporting the road wheels, means of articulation on said beam for coupling to the vehicle structure to allow the rear of the vehicle to slew on one or more of said curves or corners and the rear wheels to come into contact with the track, and a pair of spaced contact slippers hinged to the axle structure to co-operate with said guide to pick up current and steer the vehicle, said vehicles being constructed to traverse said tracks at a speed which will cause the vehicles to slew at the rear on one or more of the curves or corners unless the speed of negotiation thereof is reduced by the competitor; a competitor-operated speed control means for each competitor operable at will to control vehicle speed on one or more of said curves or corners; a plurality of electric circuits including said vehicles and said control means; and means for adjusting the electrical resistance of said circuits for equalizing the time taken per lap by the several vehicles to traverse their relevant tracks; the character of said tracks and the said adjusting means being so combined that the time per lap for traversing each of the several tracks is substantially equal for equal skill in controlling the speed of the vehicles for optimum speed on the said curves or corners.

operable at will to control vehicle speed on one or more of said curves or corners; a plurality of electric circuits including said vehicles and said control means; and means for adjusting the electrical resistance of said circuits for equalizing the time taken per lap by the several vehicles to traverse their relevant tracks; the character of said tracks and the said adjusting means being so combined that the time per lap for traversing each of the several tracks is substantially equal for equal skill in controlling the speed of the vehicles for optimum speed on the said curves or corners.

19. Race game apparatus for a plurality of competitors comprising in combination a plurality of tracks forming closed circuits, curves or corners thereon; a plurality of miniature electrically-driven automobiles or like vehicles adapted to traverse said tracks and to be guided thereby, each of said vehicles including a front axle unit comprising an axle beam supporting the road wheels, means of articulation on said beam for coupling to the vehicle structure to allow the rear of the vehicle to slew on one or more of said curves or corners and the rear wheels to come into contact with the track, and a pair of spaced contact slippers hinged to the axle structure to co-operate with said guide to pick up current and steer the vehicle, said vehicles being constructed to traverse said tracks at a speed which will cause the vehicles to slew at the rear on one or more of the curves or corners unless the speed of negotiation thereof is reduced by the competitor; a competitor-operated speed control means for each competitor operable at will to control vehicle speed on one or more of said curves or corners; a plurality of electric circuits including said vehicles and said control means; and means for adjusting the electrical resistance of said circuits for equalizing the time taken per lap by the several vehicles to traverse their relevant tracks; the character of said tracks and the said adjusting means being so combined that the time per lap for traversing each of the several tracks is substantially equal for equal skill in controlling the speed of the vehicles for optimum speed on the said curves or corners.

PATRICK GILBERT KENNEDY.
